DESIGN FOR A COMBINATION VIOLIN BRIDGE AND TAILPIECE

Myron Earl Osburn, Enid, Okla.

Application August 24, 1944, Serial No. 115,012

Term of patent 14 years

(Cl. D56—1)

To all whom it may concern:

Be it known that I, Myron Earl Osburn, a citizen of the United States, residing at Enid, in the county of Garfield and State of Oklahoma, have invented a new, original, and ornamental Design for a Combination Violin Bridge and Tailpiece, of which the following is a specification, reference being had to the accompanying drawing, forming part thereof.

Figure 1 is a top plan view of a combination

violin bridge and tailpiece, showing my new design.

Figure 2 is an end elevational view as seen from the right of Figure 1.

Figure 3 is a central vertical section on the plane of the line 3—3 of Figure 1.

I claim:

The ornamental design for a combination violin bridge and tailpiece, as shown.

MYRON EARL OSBURN.
